GEAR SHIFTING CONSOLE FOR A BICYCLE

Viktor Schreckengost, Cleveland Heights, Ohio, assignor
to The Murray Ohio Manufacturing Co., Nashville,
Tenn., a corporation of Ohio

Filed Apr. 11, 1969, Ser. No. 16,693

Term of patent 14 years

Int. Cl. D12—14

U.S. Cl. D90—1

Fig. 1

Fig. 2

FIG. 3

FIG. 4

FIG. 6

FIG. 5

FIG. 1 is a top plan view of a gear shifting console for a bicycle showing my new design;

FIG. 2 is a side elevational view thereof;

FIG. 3 is a front elevational view thereof;

FIG. 4 is a rear elevational view thereof;

FIG. 5 is an elevational view taken from the side opposite that in FIG. 2; and

FIG. 6 is a bottom plan view thereof.

I claim:

The ornamental design for a gear shifting console for a bicycle, substantially as shown.
